UNITED STATES PATENT OFFICE.

NELSON S. WELK AND ALEXANDER B. ROE, OF ATHENS, OHIO; SAID WELK ASSIGNOR
OF HIS ENTIRE RIGHT TO THE MCBEE BINDER COMPANY, OF ATHENS, OHIO.

PERFORATING MACHINE.

Application filed November 17, 1921. Serial No. 515,793.

To all whom it may concern:

Be it known that we, NELSON S. WELK and ALEXANDER B. ROE, citizens of the United States, residing at Athens, in the county of Athens and State of Ohio, have invented a new and useful Perforating Machine, of which the following is a specification.

Our invention relates to perforating machines designed for use in preparing sheets for binding, and has for its object to produce a machine of strong, durable and relatively simple construction, wherein the sheets to be perforated will be forced downwardly over stationary rotating hollow drills, with adequate means being provided for clearing the cuttings from the hollows in the drills.

A further object is to provide an efficient and quickly operated sheet perforating machine, functioning as a power driven rotating punch, (rather than a drill) the punches being hollow to receive the cuttings which will be forced therethrough to a receiving pan, thus eliminating the accumulation of waste cuttings around the machine.

A further object is to provide such a machine, constructed in such a manner that the application of pressure on the sheets to be perforated will also function to force the cuttings through the hollow drills.

A further object is to construct our machine in such a manner that the perforating drills will be below the sheets to be perforated, a yielding base, with perforations to receive the drills and permit their passage upwardly therethrough, being provided, so as to function for strengthening the drills and keeping them always in proper alignment.

Many other objects and advantages of our machine will be noted in the reading of the attached specification and claims, reference being had to the drawings, in which Figure I shows a perspective view of our machine, with leaves to be perforated in position therein and showing the platform slightly depressed from its normal position, the dotted lines indicating the normal position of the platform, and the elevated position of the parts which operate to force the platform downwardly;

Figure II shows a detail view, in eleva-

tion, of the evener device we use, the parts of the machine to which it is attached being shown in section;

Figure III is a detail view, in side elevation of one of the standards of our machine, also showing a portion of the platform and the spring which supports it and also a portion of the pressure bar and its mountings, the dotted lines indicating the normal positions of certain of the parts;

Figure IV shows a front elevation view, partially in section, taken on the line 4—4 in Figure III;

Figure V shows a vertical, sectional, view of the drills and their mountings; and

Figure VI shows a detail view, in elevation, of a part of the drills and the worm gears attached to certain of them and which mesh with the drive shaft from the motor.

Referring to the accompanying drawings the reference numeral 10 is used to indicate the base of our machine, and the numerals 75 11 and 12 companion, and parallel, standards projecting vertically therefrom. The numeral 13 indicates a crossbar mounted to, and elevated slightly from, the base of the machine, said crossbar being in a horizontal 80 plane and mounted immediately in the rear of the aforesaid standards.

The numeral 14 indicates a second crossbar mounted to, and elevated from, the first mentioned crossbar, the construction being 85 such that the two crossbars 13 and 14 are parallel and in a horizontal plane but spaced from each other. Journaled in these crossbars, and extending upwardly from the upper crossbar, are a plurality of drills 15, 90 said drills being mounted for rotation and each of same being provided with a worm gear 16 on its outer periphery, and being further provided with a second gear 17 on its outer periphery. Also journaled in the 95 crossbars are a plurality of drills which are mounted in juxtaposition with their companion drills 15, the drills 18 being provided with gears 19 to mesh with their companion gears 17 on the companion drills 15. A 100 motor 20 is secured to the base of our machine and provided with a drive shaft 21, on which are worm gears 22 and 23, designed to mesh with their respective worm gears 16 for driving of the drills 15. The worm 105 gears 16, on the drills, are reversed as to

adjacent drills and, obviously, the worm gears 22 and 23 are of the right pitch to mesh with their respective worm gears 16. The construction is such that the drive shaft 21 from the motor, in its rotation, will drive the drills 15 through the medium of the worm gears 22 and 23 meshing with the worm gears 16, and the drills 15 will drive their companion drills 18 through the medium of the gears 17 meshing with the gears 19.

All the drills are uniform in length and extend upwardly to a given point. The drills are all hollow drills, as indicated by the numeral 24, and are provided with upper cutting edges 25. A removable pan 26 is secured below the crossbars 13.

The numeral 27 indicates the assembly base of our machine, on which the sheets are assembled and evened. Normally, this base maintains a position immediately above the upper cutting edges of the drills, and the base is perforated, as shown at 28, to permit the passage therethrough of the drills. This base is mounted, for vertical slidable movement, on the standards 11 and 12, and is supported in its normal position by coil springs 29 and 30, which surround their respective standards and engage lugs 31 and 32, respectively, depending from the sides of the assembly base and surrounding their respective standards. A housing plate 33 extends downwardly from near the forward part of the assembly base, and in front of the drills, to a point sufficient to conceal the drills from observation from a point in front of the machine, the purpose of this housing being for general protection from the drilling mechanism of the machine.

The numeral 34 indicates an evener plate which assumes a position in engagement with the upper surface of the assembly base. This evener plate is secured to a rod 35 which is mounted, for slidable movement, in a lug 36, and a screw 37, mounted in the lug 36, is designed to engage the rod 35 so as to retain the evener plate in any desired position.

The numerals 38 and 39 indicate lugs, mounted for slidable movement, one on each of the standards 11 and 12, and at the upper ends thereof. In these lugs we have mounted, for rotation, gear wheels 40 and 41, respectively, which are designed to be in engagement, and proper mesh, with racks 42 and 43, respectively, extending from the upper extremity of their respective standards to a point in close proximity to the upper surface of the assembly base, when it is in its normal position. The gear wheels 40 and 41 are rigidly secured to a shaft 44, journaled in the lugs, and to the ends of this shaft we have secured projecting arms 45 and 46, respectively, which arms are joined by cross bar 47 at their upper extremities.

Also joining said lugs, and positioned in the rear of the standards, is a cross bar 48 which lies in a true horizontal position, and parallel with the assembly base. This cross bar is in line with the drills and in the under surface of the cross bar we have provided means, in line with the drills, to receive the cutting ends of the drills, so that the drills will not be destroyed, or their efficiency impaired by coming in contact with this cross bar. This cross bar 48 is designed as a pressure bar for my machine as will be hereinafter described.

In practical operation, the sheets and covers to be bound, are placed upon the assembly base 27 and evened against the evener plate 34. The motor is then started, thus obviously rotating the cutting drills. The operator then grasps the cross bar 47 and pulls it rearwardly in a rotary movement, thus rotating the shaft 44 which, in turn, rotates simultaneously the gear wheels 40 and 41. As these gear wheels are in mesh with their respective racks 42 and 43, it is obvious this movement will lower the pressure bar 48, which contacts the upper side of the cover and leaves to be bound. Pressure is then applied to the cross bar 47, thus forcing the pressure bar 48 downwardly. The cover and leaves to be bound are resting upon the assembly base 27 and, as this base yields against the compression of the coil springs 29 and 30, it is obvious the pressure of the pressure bar will force the assembly base downwardly. This brings the covers and leaves to be bound in direct engagement with the cutting drills which are rotating at high speed. The downward pressure against these drills causes the drills to go through and perforate the leaves and covers to be bound. As the drills are hollow, the cuttings caused by the drills, will be forced into this hollow portion and the continued downward pressure of the pressure bar forces these cuttings downwardly, as the drills perforate the paper. Obviously, the cuttings will fill the hollow drills and the downward pressure on the pressure bar will force the cuttings out through the bottom of the hollow drills into the receiving pan 26. As before stated, this pan is removable so that, when desired, the operator may dispose of the cuttings which have accumulated therein.

The drawings which accompany this application and the description of the same, embody the preferable construction of our device. Minor changes may be made in various parts of the machine without in any manner affecting the functions thereof, or departing from our invention, and we desire to be understood as not wishing to limit our invention by the preceding description and the drawings, but only by the claims which are hereto appended.

Having thus described our invention, what we claim and desire to secure by Letters Patent of the United States, is:

1. A perforating machine comprising a spring actuated assembly base with perforations therein; hollow drills mounted for rotation beneath the assembly base, the drills registering with the perforations; a pressure bar mounted for vertical movement above the assembly base and in alinement above the perforations; means to move the pressure bar downward to engagement with the material to be perforated and to continue said pressure downward until the drills have perforated the material and come into engagement with the pressure bar.

2. A perforating machine comprising a spring actuated assembly base with perforations therein; hollow drills mounted for rotation beneath the assembly base, the drills registering with the perforations; a pressure bar mounted for vertical movement above the assembly base and in alinement above the perforations; means to move the pressure bar downward to engagement with the material to be perforated and to continue said pressure downward until the drills have perforated the material and come into engagement with the pressure bar; means to

retain the assembly base in a normal position immediately above the drills. 30

3. In a binding machine hollow cutting drills; an assembly base mounted for slideable vertical movement on the standards of the machine, with spring actuated means to retain the said base in a normal position above the cutting drills, there being perforations in said base to register with the cutting drills; means to force the said assembly base downwardly over the cutting drills. 35 40

4. A perforating machine comprising a body portion in which a plurality of hollow drills are mounted for rotation, an assembly base to receive the material to be perforated, a pressure bar to be clamped against the material to retain it in permanent position, said pressure bar being in line with the drills and also being provided with drill receiving means which register with their respective drills; means to force the material 45 against the rotating drills, substantially as shown and described. 50
